ATTORNEY.

UNITED STATES PATENT OFFICE.

EDWARD H. REHN AND ELTON A. TOUSLEY, OF LIMA, OHIO.

HOUSEHOLD POUNDING BLOCK.

1,420,577.

Specification of Letters Patent. Patented June 20, 1922.

Application filed April 16, 1920. Serial No. 374,356.

To all whom it may concern:

Be it known that we, EDWARD H. REHN and ELTON A. TOUSLEY, citizens of the United States of America, and residents of 5 Lima, in the county of Allen and State of Ohio, have invented certain new and useful Improvements in Household Pounding Blocks, of which the following is a specification.

10 This invention relates to household articles and particularly to a device for use in cracking nuts, and in connection therewith to provide a device which can be used as a buffer or anvil for hammering or shaping objects.

An object of this invention is to provide novel means adapted to be supported on the upper leg of a user, preferably just above the knee when the user is in a sitting 20 posture, the said device being provided with means to support and partially confine nuts or the like to prevent them from flying out from under the hammering instrument; and furthermore, an object of the invention 25 is to provide a detachable anvil associated with that part of the device on which nuts are supported while being cracked, so that the implement can be used in a number of different ways, all of which will prove desirable in one way or another from time to 30 time.

A further object of this invention is to produce a device of this character which will not inconvenience the user, notwithstanding 35 a relatively hard blow is delivered to crack the nuts or to shape articles on the anvil.

With the foregoing and other objects in view, the invention consists in the details 40 of construction, and in the arrangement and combination of parts to be hereinafter more fully set forth and claimed.

In describing the invention in detail, reference will be had to the accompanying 45 drawings forming part of this specification wherein like characters denote corresponding parts in the several views and in which—

Fig. 1 is a view in elevation of the implement embodying the invention;

Fig. 2 is a sectional view, and

Fig. 3 is a top plan view with the anvil omitted.

In these drawings, 5 denotes a yoke which is adapted to overlie the upper leg above 55 the knee so that it is supported thereby, and the said yoke is relatively wide so that perceptible bearing surface is afforded and to insure against injury to the user, notwithstanding the blow on the instrument may 60 be comparatively heavy.

The top of the yoke has an upstanding boss 6 terminating in a lug 7 with a shoulder 8 at the junction of the said boss and lug for a purpose that will presently appear. 65 The upper surface of the lug is preferably recessed as at 9 to form a seat to prevent the nuts being cracked from being dislodged from the lug, and as constructed, the device has been found to prove very satisfactory 70 as a nut cracking base.

The lug 7 is preferably square in plan and fits in a socket 10 formed in the base 11 of the anvil 12, the base of the said anvil resting on the shoulder 8 which extends 75 around the lug.

While we have shown the anvil as having the configuration of an ordinary anvil of a blacksmith, we do not of course wish to be restricted with respect to the construction of 80 this feature of the device, as it is the purpose of the inventor to provide an auxiliary detachable member having a flat surface for shaping articles, and it may also have the other features shown or modifications there- 85 of.

By reason of the fact that the lug is square, it follows that the anvil may be turned to different positions, so that if found desirable, it might stand at a position at 90 a right angle to the position shown in Fig. 1, or it may be turned half way round in its adjustment.

The device constructed in accordance with this invention may be inexpensively produced on account of the fact that it can be cast, and it has been as stated, found highly useful and satisfactory in practice.

We claim:

100 In a combination implement, a yoke having a relatively wide bearing surface and of curved formation, with a concave under sur-

face and a convex upper surface adapted to embrace the leg of a user and to be supported on the top of the leg, a boss rising from the convex side of the yoke at the highest point thereof terminating in a lug with a shoulder at the junction of the boss and lug, and a member adapted to receive

impact, having a seat of the configuration of the lug and adapted to receive said lug, the lower edge of the bearing surface resting on the shoulder at the junction of the boss and lug.

EDWARD H. REHN.
ELTON A. TOUSLEY.
